UNITED STATES PATENT OFFICE.

EDWARD S. BOYNTON, OF BRIDGEPORT, CONNECTICUT.

BOOK-SEWING.

SPECIFICATION forming part of Letters Patent No. 247,475, dated September 27, 1881.

Application filed May 5, 1881. (No model.)

To all whom it may concern:

Be it known that I, EDWARD S. BOYNTON, of Bridgeport, county of Fairfield, State of Connecticut, have invented an Improvement 5 in Book-Binding, of which the following description, in connection with the accompanying drawings, is a specification.

My invention relates to book-binding, and is shown embodied in a book sewed upon the 10 method shown in United States Patent No. 211,616, granted to me January 28, 1879, to which reference may be had. In that patent a thread, which I herein call the "internal thread," was employed, that extended inside of and 15 against the fold of each signature, the entire length of the page traversing the saw-cuts, and binding-cords were sewed through each of the said saw-cuts and looped or turned around the threads within the signatures, they binding 20 the different signatures together and performing the function of the bands in an ordinary hand-sewed book, while the internal threads in co-operation therewith held the internal sheets of each signature in place. The ends of 25 the binding-cords extended beyond the ends of the said sawed cuts of the sewed book, to enable the cases to be fastened thereto in the usual manner. In this construction it was found necessary to make the binding-cords 30 quite stout, in order to give sufficient strength to the connection between the different signatures and to properly hold the cases, and as the said cord formed a loop in each signature it made the ridge at the saw-cut in some in- 35 stances objectionably large. This defect is entirely removed by my present invention, by which an exceedingly strong, flexible, and durable binding is produced, the invention mainly consisting in providing independent band- 40 pieces of usual character placed in the saw-cuts and sewed through and through by the cords by which the internal sheets of the signatures are held in place. As herein shown, the band-piece laid in the saw-cut is sewed 45 through and through by binding-cords, which are looped around internal cords, as in my former invention, thus securing the said internal threads to the band-piece, which is itself securely sewed to the back of the book. The 50 binding-cord consequently need be only of sufficient strength to properly secure the in-

ternal thread and retain the internal sheets in place, the different signatures and the cases being now held together by the strength of the independent band-piece, in addition to that 55 of the said binding-cord.

Figure 1 is a rear view of a series of signatures sewed together according to my invention, and Fig. 2 a transverse section thereof on a plane passing through one of the saw-cuts. 60

The signatures *a*, provided with saw-cuts *2*, will preferably be sewed in accordance with my invention upon a machine invented by me for this purpose, which will form the subject of a future application for Letters Patent, or 65 they may be sewed by hand, the order of the different steps in the operation varying somewhat, according to the means employed for doing the work, and not forming an essential part of my invention. In any case the bands *b*, of any suitable or usual form and material, are laid in as many of the saw-cuts *2* as is desired for the finished book, after which suitable needles supplied with the binding-threads *c* may be passed through the said bands and 70 saw-cuts to the interior of the signature and there properly operated to form a loop, *3*, (see Fig. 2,) through which the internal threads, *d*, one of which is shown in dotted lines, Fig. 1, may be passed, either by hand or by a device 75 forming part of the machine, as described in my former patent referred to. The binding-thread is then withdrawn, tightening up the loop to properly hold the internal thread, *d*, and a new signature sewed on in the same manner. 85

It is obvious that the order of steps in the operation might be reversed, the internal threads, *d*, being laid in the folds of the signatures and the binding-thread *c* carried through the band *b* and around the said internal thread, and then 90 out through the band again.

By this construction the band *b* strongly holds the different signatures together—a thing which in my former invention was done by the binding-threads *c*, which had to be made sufficiently stout for this purpose, but which in my present invention need only be strong enough to hold the internal threads, *d*, and retain the internal sheets of the signature in place. 95

The saw-cuts nearest the ends of the book 100 will preferably not be supplied with bands *b*, and the binding-cords *c* in the said end saw-

cuts will be drawn out, as described in my former patent, to bring the end of the internal threads through the saw-cut upon the back of the book, as shown at the right-hand end of Fig. 1.

5 A sufficient portion of the band-piece *b* will have to be left between the last signature of one book and the first signature of the next, as shown at 4, to be secured to the cases to 10 properly attach them to the signatures when sewed together, as the said band-pieces, being pierced by the threads in sawing, cannot subsequently be "drawn off." The ends of the binding-threads *c* will also preferably be left to 15 join upon the cases with the ends of the band-pieces *b*.

Piercing the band-pieces by the threads that secure the internal sheets of a signature in place joins the said signatures more securely 20 together than when the said band-pieces are free to slide in the saw-cuts, and makes a very firm and at the same time flexible binding, the signatures being less liable to become separated in the subsequent processes of forwarding the book.

25 It is obvious that wires or fastening-pins, such as shown in Letters Patent No. 193,109, July 17, 1877, might be employed instead of the internal threads, *d*, they being equivalent 30 thereto in their relation to the band and binding-threads.

The saw-cuts may be dispensed with, the bands *b* being merely laid across the back of

the book, and the binding-thread *c* piercing the signatures.

35

I claim—

1. The combination, with the signatures of a book and a band-piece laid across the back thereof, of threads sewed directly through the said band-piece and passed within the signatures to hold the inner sheets in place, whereby the different signatures are strongly fastened together and the sheets of each signature securely held therein, substantially as described. 40

2. The combination, with the signatures of a book, of the internal threads lying in the fold of the inner sheet, the band - pieces, and the binding-threads interlooped with said internal threads and connecting them with the said band-pieces, substantially as described. 45

3. The signatures of a book provided with a series of saw-cuts, the band-pieces therein, and the internal threads laid in the folds of the inner sheets of the said signatures, and having their ends drawn through the saw-cuts 55 nearest the ends of the sheets, combined with the binding-threads sewed directly through the said bands and interlooped with the internal threads, substantially as described.

In testimony whereof I have signed my name 60 to this specification in the presence of two subscribing witnesses.

EDWARD S. BOYNTON.
